UNITED STATES PATENT OFFICE.

RALPH MANCUSO, OF BROOKLYN, NEW YORK.

DESIGN FOR A STATUE-DOLL.

52,242.

Specification for Design. Patented July 30, 1918.

Application filed December 15, 1917. Serial No. 207,375. Term of patent 7 years.

To all whom it may concern:

Be it known that I, RALPH MANCUSO, a subject of the King of Italy, residing at New York, borough of Brooklyn, in the county of Kings and State of New York, have invented a new, original, and ornamental Design for a Statue-Doll, of which the following is a specification, reference being had to the accompanying drawings, forming part thereof.

I claim:

The ornamental design for a statue doll as shown.

RALPH MANCUSO.

Witnesses:

ALEXANDER M. SILVER,
ALOS FELISE.
